[57] CLAIM

The ornamental design for a combined dishwashing
brush, scraper and liquid disperser, shown and de-
scribed.

DESCRIPTION

FIG. 1 is a left side elevational view of a combined
dishwashing brush, scraper and liquid disperser show-
ing my new design, the right side being a mirror image
thereof;

FIG. 2 is a top view thereof;

FIG. 3 is a bottom view thereof;

FIG. 4 is a front view thereof;

FIG. 5 is a rear view thereof; and,

FIG. 6 is a sectional view taken along line 6—6 in FIG. 1.

FIG. 2

FIG. 1

FIG. 3

FIG. 6

FIG. 4

FIG. 5
